UNITED STATES PATENT OFFICE

2,416,626

SWITCH

Max Leroy Jeffrey, Shaker Heights, Ohio, assignor to The National Acme Company, Cleveland, Ohio, a corporation of Ohio

Application April 24, 1943, Serial No. 484,376

6 Claims. (Cl. 74—100)

1

This invention relates to improvements in control station switches and more particularly to switches having a snap action which provides a quick make and break for the contacts.

Although snap action switches have heretofore been contemplated, considerable difficulty has been encountered in designing a switch having a suitable snap action which will provide consistent reliable operation over long periods of time, carry relatively heavy currents and still be small enough in structure so as to utilize a minimum of space. Furthermore, these switches were not always adaptable to a large number of jobs, each usually being designed for a specific installation.

It is therefore an object of this invention to provide a snap action switch which takes up a minimum of space and has a large current carrying capacity.

Another object of the invention is to provide an improved form of snap action switch which is simple in design and rugged in construction.

Another object of the invention is to provide a switch assembly where the actual switch mechanism may be operated by pushing a button or by turning a button and wherein the buttons are interchangeable to provide push or turn button operation at any of the stations.

Another object of the invention is to provide an improved safety switch where there is no opportunity for an electric shock to the operator.

Another object of the invention is to provide a snap action switch where no partially open or closed positions are possible.

Still other objects of the invention and the invention itself will become more apparent from the following description of an embodiment thereof which description is illustrated by the accompanying drawings and forms a part of this specification.

In certain aspects the invention is an improvement of my Patent No. 2,294,559 of September 1, 1942.

In the drawings:

Fig. 1 is a front elevational view of a panel or escutcheon plate in which the switch of my invention is incorporated;

Fig. 2 is a side elevational view of the panel of Fig. 1 with certain parts broken away and shown in sections and showing in side elevation the switches mounted on the back of the panel;

Fig. 3 is a rear view in elevation of the panel of the switch of Fig. 1 with two of the switches removed and showing a rear view of two types of the operating buttons;

2

Fig. 4 is a side elevational view of one of the turn-type of button used in connection with the switch of my invention;

Fig. 5 is a rear elevational view of the button of Fig. 4;

Fig. 6 is an elevational view of one of the switch assemblies removed from the supporting panel and illustrating the side which is attached to the rear face of the panel;

Fig. 7 is a bottom plan view of one of the switch assemblies with the bottom cover plate removed and showing the snap action mechanism;

Fig. 8 is a top plan view of the switch mechanism with the cover plate removed and showing the contactor mechanism;

Fig. 9 is a vertical medial section taken on the line 9—9 of Fig. 7 and looking in the direction of the arrows;

Fig. 10 is a section taken on the lines 10—10 of Fig. 8 looking in the direction of the arrows;

Fig. 11 is a side view of a switch arm contact guide;

Fig. 12 is an end view of the contact carrying arm and rocker and their supporting shaft removed from the assembly;

Fig. 12a is a side elevational view thereof, and

Fig. 13 is a view of one of the contact carrying strips and contacts.

Throughout the drawings like parts have been designated by like reference characters.

Generally speaking the apparatus adapts itself very efficiently to installations where switches are desired for starting, stopping or jogging a machine. In this case one switch assembly adapts itself for all three of the services mentioned. By substituting different buttons in the switch panel the switch can be made to operate as a push button switch where you push to close the contacts or a push to open the contacts, operation being such that when the finger is removed from the button the switch returns to its former position; or a turn-type button such as shown in the "jog-run" position may be used which enables the switch contacts to remain in an opened or closed position depending on the direction and position to which the button is turned. In any event, the same switch mechanism suffices for all operations.

Although a particular type of supporting panel or escutcheon plate is shown in the drawings, it will be observed that the number of stations is merely a matter of choice and they may be increased or decreased in number to suit the particular conditions where control is desired.

In Fig. 1, by way of illustration, I have shown 55 a panel or escutcheon plate 10 having edge open-

ings 11 which enable the plate to be secured to a suitable support or in a housing.

The panel is provided in its mid portion with three openings 12 therethrough which are vertically aligned. A relatively low annular boss 13 is provided around each of the openings 12 on the front side of the panel. The rear of the panel around each of the openings 12 is provided with an irregularly shaped projection or boss 14 the contour of which is best shown in Fig. 3 and which constitutes a housing for the operating button and a support for the switch assemblies. Each of these projecting housings has an enlarged bore 15 extending towards the opening 12 and terminating in a shoulder 16. The opening or bore 12 receives in sliding engagement the cylindrical end 17 of a push button and the bore 15 likewise receives a flange 18 on the push button. The push button may be moved inwardly from the position shown in Fig. 2 its outward movement being limited by the flange 18 contacting with the shoulder 16. The push button is also provided with an annular groove 19 which surrounds a central pin 20 which extends flush with the inner face of the flange 18 and is adapted to contact the operating pin 21 of the switch mechanism indicated generally at 22.

As best shown in Fig. 3 each of the projecting bosses is provided with two laterally extending bosses 24 extending above and below a center line through the main boss and provided with threaded openings 25 for the reception of screws 26 which extend through bosses on the switch assembly housings and hold them in place on the bosses 24. Three such switch assemblies are provided in this specific instant each of which has sets of terminal screws 27 and 28 which extend through the end of the housing into strips which carry fixed contacts on the interior of the housing.

Operation of the switch 22 in the "start" and "stop" positions, as shown in Figs. 1 and 2, is effected by pushing the button 17 inwardly, the pin 20 of the button engaging the operating pin or plunger 21 of the switch which actuates the mechanism, later to be described, inside of the switch housing. It will be noted that these push buttons lie flush with the surface of the panel and the ring 13 and therefore cannot be accidentally operated, since it is necessary to push the button inward depressing it below the front surface of the panel in order to operate the switch mechanism.

The operating lever or button for the "jog-run" position, as previously stated, is a turn type of button, being so designed that it may be turned to hold the contacts in the proper position for the "jog" or "run" position. This is effected by a cam action of the button which either holds the plunger 21 of the switch 22 in or out, the plunger being shown in the out position for "run" and it being contemplated that it will be cammed inward for "jog."

As best shown in Figs. 2, 4 and 5, the "jog" button is provided with a handle or finger grip 30 which is adapted to protrude from the face of the panel 10. The handle is supported by a cylindrical body 31 which is rotatably journaled in the opening 12 in the panel. The body 31 has integral therewith a pair of segments 32 having surfaces 33 which are semi-circular and adapted to ride in the enlarged portion 15 of the bore. A central bore 34 is provided which extends from the rear of the button into the body 31 toward the handle. (Figs. 4 and 5.)

The wall of the body 31 which defines the bore 34 between the segments 32, is provided with two diametrically opposed cam surfaces each of which comprises a low flat portion 36, an inclined and rising portion 37, and an upper portion 38 which has a seat the purpose of which will hereinafter more clearly appear. As best shown in Fig. 3 the bosses 14 are provided with diametrically opposed notches 39 extending from the rear edge of the boss towards the panel. These notches provide guideways for a pin 40 which extends across the opening and is adapted for engagement with the cam surfaces 36 of the button. It will be seen that when the button is rotated counterclockwise from the positions shown (Figs. 1 to 3) that the cam surfaces 37 engage the pin and force it outward toward the edge of the boss, while rotation of the pin is prevented by the guideways.

In the position as shown in Fig. 2 this pin rests on the lower flat surface 36 and when the button is rotated clockwise as viewed in Figs. 3 and 5 the cam surfaces 37 engage the pin and push it outward in the guideways until it comes to rest in the seat 38. The button may be rotated approximately 90° during this operation and the amount of rotation is limited by the faces 41 on the segments 32 which engage with the pin 40.

As can best be seen from Fig. 2, the central portion of the pin also lies against the end of the operating plunger 21 of the switch. Therefore, when the button is moved counterclockwise the pin is moved outwardly in the slots 39 and the central part of the pin bearing against the plunger 21 moves the plunger to the right as shown in Fig. 2. The pin 40 will seat in the depression 38 and hold the plunger 21 in its inwardly pressed position. When it is rotated in the opposite direction the pin is moved out of the notch 38 and the spring pressure from the plunger 21 on the pin 40 is sufficient to cause the camming action of the pin 40 on the cam 37 to rotate the button back to its original position where the pin is seated in the bottom flat portion 36.

It should be noted that each one of the bosses is provided with the notches 39 and therefore the mechanism shown in the lower "jog, run" position may be substituted in any of the other positions when desired or all of the positions may be controlled by the turn-type button or all of them controlled by push type buttons.

As previously stated the switch assemblies are all the same. Therefore a description of one will suffice for all. As can best be seen from Figs. 2 and 6 the housing is substantially rectangular in shape comprising a substantially rectangular outer wall 50 closed on opposite sides by plates 51 and 52 which are held in place by screws 53 that extend through the plates and are threaded into the housing wall. The interior housing is divided into two separate chambers by a partition 54 that extends longitudinally of the housing between the end walls. One chamber provides a housing for the contact mechanism and the other chamber houses the snap action mechanism.

As best shown in Fig. 9 the partition is provided with a thickened portion 55 at one end which has an opening 56 therethrough in which is rotatably journaled a pin 57. A rocker member 58 is secured to one end of the pin on one side of the housing and a contact carrying arm 59 is secured to the pin on the opposite side of

5

the partition both being locked to the pin and adapted to swing in unison.

The mechanism for operating the rocker arm 58 will first be described, it being in many respects similar to that of my aforementioned patent. The purpose is to provide means for quickly rocking the shaft 57, and through it the contact carrying arm. In effecting this movement the rocker 58 is provided with a pair of arms 60 that extend laterally from the main body and a flat roller engaging face 61 as best shown in Fig. 7. The rocker is rotated by a spring pressed roller in the end of a lever, which roller bears against the face 61. The rocker is held against rocking by pawls 62 until released by the lever. The pawls 62 are pivotally supported on pins 63 at points opposite the ends of the rocker, the pins 63 being carried by the partition. The ends 15 of the rocker are provided with sharp edges 64 which are adapted to engage with shoulders 65 on the pawls. The pawls are held spring-pressed towards the rocker by springs 66 interposed between the pawls and the partition and seated on pins on the partition and in recesses in the sides of the pawls.

The member for rocking the rocker comprises a lever 67 which is provided with a bifurcated end 68 that is slidably engaged with a circular boss 69 connected to the end of the housing by a neck 70. The space between the bifurcated ends provides for a close but sliding fit with the circular boss 69. In the base of the lever there is provided a bore 72 which opens into the apex of the bifurcated portion and in which there is disposed a helical spring 73, one end of which seats against the end of the bore 72 and the other end of which engages the boss 69. The other end of the lever is provided with a roller 74 journalled on a pin 75 that is seated in a U-shaped slot 76 extending transversely across the end of the lever.

It will thus be seen that the spring 73 holds the lever with the roller in spring-pressed engagement with the face 61 of the rocker. Means, later described, is provided for moving the lever 67 about its fulcrum 69. In this instance, looking at Fig. 7, the lever 67 swings about the pivot 69 moving the roller 74 under pressure of the spring 73 across the face 61 of the rocker arm. When it passes the pivot point 57 of the rocker arm the spring pressure tends to rotate the rocker clockwise as viewed in the figure but such rotation is prevented because the sharp edge 64 is engaged against the shoulder 65 of the pawl. This allows a certain amount of kinetic energy to be built up which is released when the side of the lever 67 hits the boss 76 on the end of the pawl 62 and releases the rocker which is then quickly rotated by the pressure of the spring 73. This movement is transferred by the pin 57 to the contact carrying arm 59. During the swinging movement the lever 67 can slide on its fulcrum 69.

The lever 67 is moved by the plunger or operating pin 21. This pin as can best be seen in Figs. 7 and 10 is journalled in a pair of bosses 80 disposed in the side walls. One end of the pin is provided with a bore 81, in which a helical spring 82 is disposed, being engaged with the side wall 50 which closes the ends of the bore, and the other end being seated in the bottom of the bore 81. This tends to urge the plunger 21 outward through the opposite side wall. The plunger is provided with a square notch 84, in its mid portion that opens toward the lever 67. A pin 85 is pivotally carried by the lever 67 and has a square head 86 that is seated in the notch 84. It will

6

thus be seen that when the pin 21 is pressed inward that the walls of the notch 84 engage the head 86 and through the pin rocks the lever counterclockwise; and that when the pin is released the spring 82 returns the plunger and the lever back to its original position.

As best shown in Fig. 9 the contact lever, which is pivotally supported by the pin 57 extends upward therefrom between pairs of fixed contacts 88 which are connected to the terminals 28 and 21. The end of the arm, Figs. 12-13, carries pairs of contact strips or bars 90 each of which has contacts 91 for making an electrical connection between the contacts 88. It will be understood at this time that as viewed in Fig. 8 only one of the fixed contacts of each pair can be seen but that the other contact is immediately behind and spaced therefrom. The contacts 88 are secured in place in the end of the housing by a block 89 which clamps the strips that carry the contact bodies against the end of the housing, a screw 89' extending through the housing and being threaded into the block, as best illustrated in Fig. 9. These contacts being adapted to be engaged by the contacts 91 on each of the bars 90.

As best shown in Figs. 8, 9 and 13 the contacts 91 are carried by a bar 90. This bar is provided with notches at 92 for engagement with a contact retainer guide 93. The contact retainer guide 93, Fig. 11, comprises a square loop 95 the portions 95a and 95b of which provide guides for the contact bar and the end 95c of which limits the outward movement contacts. It is riveted to the lever at 94 and the end 95b extends through a notch in the end of the lever. The contact bars are thus movably supported on opposite sides of the end of the contact arm. The contact arm is provided with a pair of openings 98 at the end through which helical springs 99 extend, the ends of the springs being engaged on pins on the backs of the bars, to thus hold each of the bars spring-pressed toward the sides 95c of the retainer loop 93.

The end of the lever moves in an arcuate direction between the fixed contacts, therefore, when the springs are compressed due to the movable contacts being engaged with the fixed contacts it causes the movable contacts to first engage the fixed contacts off center and then as the movable contact bar slides on the straight guide the movable contacts slide on the fixed contacts toward the center and finally come to rest in axial alignment with each other. In this manner the movable contacts engage the fixed contacts both on the make and break with a wiping action which assists materially in keeping the contacts clean and thus lengthens the life.

It will thus be seen that I have provided an improved snap action mechanism which is very simple in its operation. Furthermore, I have provided a simple and yet rugged construction in a relatively small mechanism which allows the switch to carry currents exceedingly large for such a small mechanism. Furthermore, it will be seen that due to the double chamber construction wherein the side having the contacts is isolated from the other mechanism that there is less danger from sparking due to the break of the contacts when the device is disposed in an explosive atmosphere, and no danger to the operator from the flash back.

It will also be seen that I have provided a push button control that is exceedingly versatile inasmuch as substantially the same mechanism may be used for either a push or a turn-type button

switch by merely substituting a cam type button and pin for the simple button.

Having thus described my invention I am aware that numerous and extensive departures may be made therefrom without departing from the spirit or scope of the invention as claimed herein.

I claim:

1. A snap mechanism for a switch or the like comprising a support, a rocker, pivot means carried by the support for supporting the rocker on said support, means for rocking the rocker including a lever, a roller carried by the lever and engaging the rocker, said lever having one end formed with a fork having spaced parallel side walls, a pivot for the lever carried by the support and having curved surfaces, said forked portion of the lever being disposed on said lever pivot and with the sides of the fork in tangential engagement with the pivot, spring means disposed between the lever and the pivot urging the lever toward the rocker, said lever being slidable on said pivot, means for swinging said lever comprising a plunger, reciprocably carried by the support and a cross head carried by said lever, said plunger being formed with a way for receiving said cross head and spring means for urging said plunger in a direction to move said lever.

2. A snap mechanism for a switch or the like comprising a support, a rocker, pivot means carried by the support for supporting the rocker on said support, means for rocking the rocker including a lever, a roller carried by the lever and in engagement with the rocker, said lever having one end formed with a socket comprising spaced parallel side walls, a pivot for the lever carried by the support and having a cylindrical surface, said socket portion of the lever being disposed on said pivot and with the sides of the socket in tangential engagement with the pivot, said lever being formed with an axial bore opening toward the pivot and spring means seated in said bore and in engagement with the pivot urging the lever toward the rocker, said lever being slidable on said pivot, means for swinging said lever comprising a plunger reciprocably carried by the support and a cross head carried by said lever, said plunger being formed with a way for receiving said cross head and spring means for urging said plunger in a direction to move said lever.

3. A snap mechanism for a switch or the like comprising a support, a rocker, pivot means carried by the support for supporting the rocker on said support, means for rocking the rocker including a lever, a roller carried by the lever and engaging the rocker, said lever having one end formed with a fork having spaced parallel side walls, a pivot for the lever carried by the support and having curved surfaces, said forked portion of the lever being disposed on said lever pivot and with the sides of the fork in tangential engagement with the pivot, spring means disposed

between the lever and the pivot urging the lever toward the rocker.

4. A snap action mechanism including a housing, a rocker member, pawls for alternate engagement with the ends of the rocker member, means to rock the rocker member, comprising a lever swingably disposed opposite the rocker member and having a roller in engagement therewith, pivot means for said lever comprising a boss carried by the housing, said lever being formed with a socket and seated on said boss and spring means acting between the lever and the boss to hold the lever with the roller in engagement with the rocker member.

15 5. A switch of the class described including a contact carrying arm and a rocker for moving said arm connected thereto, means for moving said rocker including a lever operatively disposed in engagement therewith, pivot means for said lever including a boss, a forked end for said lever, said boss having curved sides for tangential bearing engagement with the inner sides of said forked end, said lever being slidable on said boss and spring means disposed between the boss and the lever, urging the lever toward the rocker.

20 6. A housing having a partition therethrough dividing the housing into chambers, switch means disposed in one of said chambers and including a swingable contact carrying member, means for pivotally supporting and operating said contact carrying member extending through said partition into the other chamber, means for rotating said carrying member disposed in the other chamber and including a rocker disposed on the operating member, lever means for operating said rocker comprising a swingable lever having end engagement with the rocker and movable over the rocker surface to rock the same, spring means for holding said lever in contact with the rocker, and means for operating said lever including a plunger slidably carried in said partition and having at least one end extending beyond the confines of the housing and means on said lever connecting said lever to said plunger.

45 MAX LEROY JEFFREY.
